US00D597371S

(12) **United States Design Patent**
Tosdale et al.

(10) **Patent No.:** **US D597,371 S**
(45) **Date of Patent:** **** Aug. 4, 2009**

(54) **FOOD PAN**

(75) Inventors: **David R. Tosdale**, Manitowoc, WI (US);
Theresa M. Mayer, Sheboygan, WI (US)

(73) Assignee: **The Vollrath Company, L.L.C.**, Sheboygan, WI (US)

(**) Term: **14 Years**

(21) Appl. No.: **29/324,933**

(22) Filed: **Sep. 23, 2008**

(51) **LOC (9) Cl.** **07-02**

(52) **U.S. Cl.** **D7/354**

(58) **Field of Classification Search** D6/406.3; D7/323, 354–361, 417, 543–545, 550.1, 551.1, D7/552.1, 553.2, 554.3, 566, 584–586; D9/414, D9/430, 434, 456, 745, 756, 761; D24/123; D28/73; 99/324, 339, 422, 426, 446, 448, 99/450; 108/43; 220/573.1–573.4, 574, 220/600–60, 610, 669, 672–675, 912; 224/604; 249/66.1, 117, 119, 122–127, 155–156, 160; 604/132, 317

(57) **CLAIM**

We claim the ornamental design for a food pan, as shown and described.

DESCRIPTION

FIG. 1 is a top perspective view of a first embodiment of the claimed design;

FIG. 2 is a top view thereof;

FIG. 3 is a bottom view thereof;

FIG. 4 is a left side view thereof;

FIG. 5 is a right side view thereof;

FIG. 6 is a front view thereof; and,

FIG. 7 is a rear view thereof.

The broken lines in the drawings are for illustrative purposes only and form no part of the claimed design.
